Patented Dec. 14, 1915.

Inventor:
Henry H. Finn

UNITED STATES PATENT OFFICE.

HENRY H. FINN, OF ORONO, MAINE.

CAR-STAKE.

1,163,746.

Specification of Letters Patent. Patented Dec. 14, 1915.

Application filed July 9, 1915. Serial No. 38,978.

To all whom it may concern:

Be it known that I, HENRY H. FINN, a citizen of the United States, residing at Orono, in the county of Penobscot and State of Maine, have invented certain Improvements in Car-Stakes, of which the following description, in connection with the accompanying drawings, is a specification, like reference characters on the drawings indicating like parts in the several figures.

Before a flat car can be loaded with lumber, railroad ties, telephone poles or similar material, it is necessary to equip the car with stakes that will hold the load in its proper position on the car. The usual practice at the present time is to insert stakes made of fairly large timber into U-shaped straps or sockets provided on the outer sides of the sills of the car. This operation is wasteful both of time and of lumber and it has, therefore, been proposed heretofore to equip flat cars with permanent stakes which would save the time and material wasted in following the usual practice. These devices, however, have not gone into use to any substantial extent so far as I am advised due, apparently, to the fact that they either are too expensive or complicated to be practical, or that they require too radical changes in the construction of the car.

The present invention aims to devise a car stake which shall be simple in construction; cheap to manufacture; can be readily attached to any flat car; and shall be thoroughly practical.

The invention will be readily understood from the following description of one embodiment thereof, reference being made to the accompanying drawings, in which—

Figure 1 is a view in side elevation of a car stake constructed in accordance with the invention; and Fig. 2 is a vertical, sectional view on the line 2—2, Fig. 1.

The device shown in the drawings comprises a base 2 adapted to be secured to the side of the sill of a car by means of bolts or similar fastening devices, and a stake 4 which is pivoted to the base 2 by a bolt 5 so that it can swing either into a vertical, operative position in which it is shown in full lines, or into a horizontal, inoperative position, as indicated in dotted lines in Fig. 1. Mounted at one side of and below the pivot 5 is a large stationary lug 6 which is so positioned that the stake rests on the upper surface of the lug when the stake is in its hori-

zontal position, and bears against the end surface of the lug when the stake is in its vertical position. In order to lock the stake in its operative or vertical position a stop 8 is pivoted to the base 2 on the side of the stake opposite to the lug 6, and is arranged to be swung into contact with the stake, as shown in Fig. 1, or to be moved into the dotted line position indicated in Fig. 1 where it will permit the stake to be swung down into its inoperative position. A small lug 10 limits the downward movement of the stop 8, the weight of the stop tending to hold it against this lug. The two parts 6 and 8 would hold the car stake in its vertical position without the aid of other positioning devices but I prefer also to mount above the stop 8 another stationary lug 9 where the stake will swing into contact with it when in its operative position so that the lug will cooperate with the parts 6 and 8 in giving the stake additional stability.

The dimensions of the parts, of course, will be proportioned in accordance with the requirements of individual cases but for most purposes it is preferable to employ an extension 12 arranged to telescope within the part 4. This extension is provided with a series of notches 14 with any one of which a pawl 16, pivoted on the part 4, can engage and thus hold the extension in different positions of adjustment with reference to the stake. The notches preferably are made square and the end of the pawl is squared so that it will prevent the extension from sliding in either direction. This pawl also serves to hold the extension in the stake when it is in its horizontal position. A spring 17 acts on the pawl to hold it normally in engagement with one of the notches 14. A number of these devices are secured to each of the side sills of a car. The stake used at the right hand end of the car should have the lugs 6 and 9 and the stop 8 reversed so that the stake 4 could swing to the left instead of moving into its horizontal position, and thus would not project beyond the end of the car. When not in use, these stakes are folded down beside the sill of the car where they are entirely out of the way; but when in use, they are swung up into the position in which the stake 4 is shown in Fig. 1 and the extension 12 is pulled up to the desired height and held in this position by the pawl 16. The knob at the upper end of the extension affords a convenient means

for fastening together the upper ends of any two stakes on opposite sides of the car by means of a wire or rope. It is a usual practice to lash the opposite pairs of stakes together in this manner. The lugs 6, 9 and 10 obviously can be cast with the base 2 provided it is desired to use cast metal in making the device, or these parts can be formed separately and secured to the base 10 plate.

Having thus described my invention, what I claim as new and desire to secure by Letters Patent of the United States is:

1. In a car stake, a base, a stake pivoted 15 on said base for swinging movement into either a vertical or horizontal position, a stationary lug mounted on said base in position to be engaged by said stake when it is in an upright position, and a pivoted stop 20 mounted on said base to bear against said stake and hold it against said lug.

2. In a car stake, a base adapted to be secured to the sill of a car, a stake pivoted on 25 said base for swinging movement into either a vertical or horizontal position, a stationary lug on said base at one side of said pivot so positioned that the stake rests upon the upper side of the lug when the stake is in its horizontal position and bears against the 30 end of the lug when the stake is in its vertical position, and a pivoted stop mounted on said base and arranged to bear against the side of said stake opposite said lug or to be moved out of contact with the stake.

3. In a car stake, a base adapted to be secured to the sill of a car, a stake pivoted on 35

said base for swinging movement into either a vertical or horizontal position, a stationary lug on said base at one side of said pivot so positioned that the stake rests upon the 40 upper side of the lug when the stake is in its horizontal position and bears against the end of the lug when the stake is in its vertical position, a pivoted stop mounted on said base and arranged to be moved into or out 45 of contact with the side of said stake opposite said lug, and a second lug mounted above said stop in position to be engaged by the stake when it is in its vertical position.

4. In a car stake, a base constructed to be 50 secured to the sill of a car, a stake pivoted on said base for swinging movement into either a vertical or a horizontal position, a stationary lug mounted on said base at one side of and below said pivot in position to 55 be engaged by said stake when it is in an upright position, a stop pivotally mounted on said base and arranged to be moved into or out of contact with the side of said stake 60 opposite said lug and operative to hold said stake against said lug when the stake is in its vertical position, and a second lug mounted on said base in position to bear against the side of the stake opposite to said first lug at a point above said pivot when the 65 stake is in its vertical position, said stop being movable to permit the stake to swing into its horizontal position.

In testimony whereof I have signed my name to this specification.

HENRY H. FINN.
